UNITED STATES PATENT OFFICE.

EDWARD DENIVELLE, OF MOUNT VERNON, AND JOSEPH COSGROVE, OF YONKERS, NEW YORK.

DESIGN FOR A STATUETTE.

SPECIFICATION forming part of Design No. 36,212, dated February 3, 1903.

Application filed September 4, 1902. Serial No. 122,134. Term of patent 3½ years.

To all whom it may concern:

Be it known that we, EDWARD DENIVELLE, a citizen of France, residing at Mount Vernon, and JOSEPH COSGROVE, a citizen of the 5 United States, residing at Yonkers, in the county of Westchester and State of New York, have invented and produced a new, original, and ornamental Design for a Statuette, of which the following is a specification, reference being had to the accompanying drawings, forming part thereof.

Figure 1 is a front view, Fig. 2 a side view, and Fig. 3 a rear view, of the statuette, which represents a tramp standing with his hands 10 in his trousers-pockets. His head B is turned slightly to the left, and he has a tin can A for a hat. His neck is long and slim, and he has a very decided "Adam's apple." The 15 eyes are large and show the whites prominently. There is hardly any bridge to his nose, and the end of it turns upward. His

upper lip is very long and is represented as being covered with a light growth of hair. He has no chin, his face dropping straight back from his short lower lip to his neck. His 25 ears are normal; but he only has a fringe of hair on the lower part of the back of his head between the ears. His body is full and rounded, the parts C and D indicating tears in his clothing, E a hole, F a patch, and G two buttons on his coat. His legs are slightly bent forward at the knees, and H represents a hole, and I a patch on his trousers. J represents his shoes.

We claim—

35 The ornamental design for a statuette, as herein shown and described.
